UNITED STATES PATENT OFFICE

FRANCIS H. HUNT, OF LEONIA, NEW JERSEY, ASSIGNOR TO RAYMOND CONCRETE PILE COMPANY, OF NEW YORK, N. Y., A CORPORATION OF NEW JERSEY

APPARATUS FOR DRIVING HOLLOW CYLINDERS

Application filed April 11, 1927. Serial No. 182,761.

This invention pertains to apparatus for driving hollow cylinders used in the building of foundations for buildings, bridges, etc.

For such work hollow metallic cylinders are used in a variety of ways, and the present invention is valuable in connection with any of the methods which call for the driving of the cylinders into the ground.

For the purpose of illustration, however, the operation of the apparatus is illustrated in connection with cylinders sunk in the method known commercially as the Gow system. In that system a comparatively short hollow cylinder is driven into the ground and the space within the cylinder is then excavated in any convenient manner. Then a second cylinder, of slightly smaller diameter, is set concentrically within the first and driven until its upper end is at nearly the same level as the bottom of the first cylinder. The second cylinder is then excavated and a third cylinder, of smaller diameter than the second, is driven, and so on until the desired depth of excavation is reached, generally at bed rock, whereupon the cylinders are filled with concrete to form a column suitable for supporting a superstructure.

The cylinders are of large diameter, and considerable force is required to drive them. The driving force is all concentrated on the thin rim. When certain kinds of soil are encountered it is difficult to apply sufficient driving effort to the cylinder without cutting or crumpling the rims where the blows of the hammer are applied.

Since the Gow cylinders are of various diameters, it is necessary that the driving mechanism be readily adaptable for those diameters.

It is also necessary to provide the driving means with devices to keep each cylinder properly aligned and concentric with the cylinder that surrounds it.

It has been customary to drive the cylinders with pile drivers of the ordinary type, placing temporary heads or cross bars of various kinds on the cylinders and directing the blows of the pile driver on the center of the temporary head.

The principal object of the invention is to

provide a driving mechanism designed especially for the driving of hollow cylinders or pipes and thereby solve the above problems.

Further and other objects and advantages will be hereinafter set forth in the accompanying specification and claims, and shown in the drawings, which by way of illustration show what is now considered to be the preferred embodiment of the invention.

Fig. 1 is a front view, partly in cross-section, of the apparatus in position for driving a cylinder.

Fig. 2 is a view on line 2—2 of Fig. 1.

Fig. 3 is a cross-section on line 3—3 of Fig. 1.

Fig. 4 is a cross-section on line 4—4 of Fig. 1.

Fig. 5 is a view on line 5—5 of Fig. 1.

Fig. 6 is a detail cross-section showing method of keying the removable jaw to the anvil casting.

In Fig. 1, 10 designates a steel cylinder driven into the ground, and 12 is a cylinder being driven further into the ground inside of and concentric with cylinder 10 after cylinder 10 has been excavated. In practice it is common to make each cylinder two inches smaller in diameter than the cylinder surrounding it. The thickness of the cylinder walls is usually about $\frac{1}{4}$ inch; therefore the space 14 between the cylinders is approximately $\frac{3}{4}$ inch.

Resting on top of cylinder 12 is a pair of anvils 16. These anvils are diametrically opposite each other (Fig. 3), and each anvil has an arm 18 extending toward the other anvil. Arms 18 pass one on each side of the web of I-beam 20 (Figs. 2 and 3).

On each side of I-beam 20 is a plate 22, secured by rivets 23 along its upper and lower edges to the flanges of I-beam 20, thereby forming a tubular channel on each side of the I-beam, between the web of the beam and plate 22. Arms 18 are so shaped and located that each one fits within one of the tubular channels so formed.

Plates 22 and the web of beam 20 are drilled with a pair of holes 24, one above the other, through either of which may be passed a bolt 26. Arms 18 are drilled with two

rows of holes 28, shown dotted in Fig. 1 and in cross-section in Fig. 3.

With the above structure in mind it is evident that the distance between anvils 16 may be varied by sliding arms 18 back or forth in the tubular channels, and that the anvils may be retained in any desired position by aligning a hole 28 in each arm 18 with one or the other of holes 24 and passing a bolt 26 therethrough. Holes 28 are so spaced and arranged as to permit adjusting the positions of anvils 16 to fit the rim of each size of cylinder.

Each anvil 16 is provided with a downwardly and inwardly projecting lip 30 shaped on its outer surface to roughly fit the inner circular surface of the cylinder, as indicated by dotted lines in Fig. 3.

Each anvil 16 is also provided with a removable jaw 32 having a downwardly projecting lip 34 so shaped as to roughly fit the inner surface of cylinder 10 and the outer surface of cylinder 12. Jaw 32 is slipped into place from either side of anvil 16 in a slot provided to accommodate it. The jaw is prevented from radial motion by the downwardly extending portion 36, and from endwise motion by keys 38 which have upwardly extending ears 40 fitted into corresponding sockets in jaw 32. After the jaw is positioned in anvil 16 the projecting ends of keys 38 are bent down as shown (Figs. 6 and 7).

The driving impact is all transmitted to the cylinders through jaws 32, therefore the jaws are made of hardened steel to reduce wear, and are made easily removable so as to be readily replaceable when necessary.

Extending upwardly from each anvil 16 is a guide rod 42. Each rod 42 has an eye at its lower end through which passes a horizontal pin 44 fitted to a hole drilled in the anvil. In the upper portion of each anvil is a recess 46 surrounding the lower portion of rod 42 and having a horizontal bottom on which is placed a steel washer 48. Resting on washer 48 is a cylindrical block 50, of wood or other shock-absorbing material.

Guided for vertical movement on each rod 42 is a hammer casting 52. Each casting 52 is lined with a steel pipe 54 for contact with rod 42, and the lower end of the casting is reduced to a cylindrical boss 56 of slightly smaller diameter than wood block 50.

The upper end of each hammer casting 52 is provided with a pair of webs 58. Through each pair of webs is fitted a horizontal pin 60 to which are fastened the lifting chains 62. Below webs 58 is a boss 64 into which is secured, by pin 66, the end of a horizontally projecting pipe. The pipes project toward each other and are of different diameters, so that the smaller one 68 slips inside the larger one 70.

The inner pipe is drilled with a series of

holes 72 (Fig. 4), and the outer pipe has one hole 74, all holes being of a diameter to accommodate a bolt 76. It is apparent that by the above arrangement the upper ends of hammers 52 and rods 42 may be adjusted to correspond to the distance between anvils 16, so that guide rods 42 are vertical.

In operation, anvils 16 and pipes 68-70 are set so that rods 42 are vertical and the outer surfaces of the anvils will just slip inside the cylinder 10 already driven. Lips 30 will guide the upper end of the inner cylinder into the space between anvil lip 30 and jaw lip 34, until the under side of the body of removable jaw 30 rests on the top of pipe 12.

The outer curvature of lip 16 and inner curvature of lip 34 are fixed, whereas the diameters of the pipes being driven vary through quite a range. This variation, however, is no hindrance to the operation of the apparatus, because the jaw 34 is a sloppy fit in anvil 16, and because the pipe is so thin as to readily adapt itself to the curved space provided for it.

Anvils 16 being in place on the inner pipe 12, and guide rods 42 being vertical, the driving operation is carried on by lifting hammers 52 by means of chains 62 and dropping the hammers on wood blocks 50 through which the impact is transmitted by rings 48 and anvils 16 to the cylinder.

The apparatus have been found very satisfactory and efficient in service. It is readily adjustable to different cylinders, and drives them rapidly. It is flexible and loose-jointed so as to be free from binding in operation, while the character of the blow may be varied by changing the travel of the hammers on guides 42, or by changing to hammers of different weight.

It is found that the use of this apparatus almost completely eliminates the damage done to the rims of the cylinders by previous devices.

It is to be understood that the invention is not limited to the specific construction herein illustrated and described but may be embodied in other forms without departure from its spirit.

I claim—

1. In a device for driving hollow cylinders, in combination, a plurality of anvils, means for adjusting said anvils relatively to each other to fit cylinders of different diameters, and a hammer adapted to operate on each of said anvils.

2. In a device for driving a thin metal cylinder into the ground, in combination, a pair of anvils adapted to rest upon and closely engage the inner and outer surfaces of widely separated portions of the upper rim of said cylinder, means for adjusting said anvils to fit cylinders of different diameters, a hammer for each of said anvils, and means

to guide each of said hammers to operate on its corresponding anvil.

3. In an apparatus for driving a hollow cylinder within an outer hollow cylinder, in combination, an anvil structure adapted to be guided by said outer cylinder and to guide said inner cylinder; said anvil structure comprising a pair of anvils adjustable relatively to each other, and means for holding 10 said anvils in adjusted position.

4. In an apparatus for driving a hollow cylinder within an outer hollow cylinder, an anvil structure comprising in combination, a plurality of anvils, and adjustable means for

15 adapting said structure for driving cylinders of different diameters; said outer cylinder serving to guide said structure, and said structure serving to guide said inner cylinder by engaging its inner and outer surfaces 20 at widely separated portions of the cylinder.

5. An anvil for driving hollow cylinders, comprising in combination, a downwardly extending projection, and a removable jaw having a downwardly projecting portion, 25 said projections being adapted to engage between them the upper rim of the cylinder to guide the cylinder while being driven.

6. An anvil structure for driving hollow cylinders, comprising in combination, a plurality 30 of interconnected anvils arranged to rest on the upper rim of the cylinder at widely separated points thereof, each anvil being provided with a pair of downwardly extending projections adapted to engage the inner 35 and outer surfaces of said rim.

7. An anvil structure for driving a hollow cylinder within another hollow cylinder, comprising in combination, a plurality of interconnected anvils arranged to rest on the 40 upper rim of the inner cylinder at widely separated points thereof, each anvil being provided with means for maintaining guiding contact with both inner and outer cylinders for the purpose set forth.

45 8. In an apparatus for driving a hollow cylinder, in combination, an anvil structure adapted to engage the upper end of the cylinder at a plurality of widely separated points and a hammer adapted to strike said 50 anvil structure above each point of contact with said cylinder; said hammers being interconnected for substantially simultaneous operation.

55 9. In an apparatus for driving a hollow cylinder, in combination, an anvil structure adapted to engage the upper end of the cylinder at a plurality of widely separated points and a hammer adapted to strike said anvil structure above each point of contact with 60 said cylinder; each of said hammers being guided for operation on a vertical rod pivotally connected to said anvil structure at a point adjacent the point of contact with said cylinder.

65 10. In an apparatus for driving a hollow

cylinder into the ground, a plurality of hammers, means aside from said cylinder for guiding said hammers for operation in substantial alignment with the rim of said cylinder at widely separated points thereof, and 70 means for supporting an anvil between each of said hammers and said rim to transmit the blow of the hammer to the rim, said anvils being interconnected by an adjustable structure to adapt them to cylinders of different 75 diameters, and said guiding means being secured to said anvils and settable into operative relationship with said anvils when said interconnecting structure is adjusted.

11. In an apparatus for driving a hollow 80 cylinder into the ground, a plurality of hammers, means aside from said cylinder for guiding said hammers for operation in substantial alignment with the rim of said cylinder at widely separated points thereof, and 85 means for supporting an anvil between each of said hammers and said rim to transmit the blow of the hammer to the rim, said anvils being interconnected by an adjustable structure to adapt them to cylinders of different 90 diameters, and settable means being provided for adjusting the guiding means to maintain 95 said hammers in proper relationship with said anvils.

12. In an apparatus for driving a hollow 95 cylinder into the ground, a plurality of hammers, means aside from said cylinder for guiding said hammers for operation in substantial alignment with the rim of said cylinder at widely separated points thereof, 100 and means for supporting an anvil between each of said hammers and said rim to transmit the blow of the hammer to the rim, said anvils being interconnected by an adjustable structure to adapt them to cylinders of 105 different diameters.

13. In an apparatus for driving a hollow cylinder into the ground, a plurality of hammers, means aside from said cylinder for guiding said hammers for operation in substantial alignment with the rim of said cylinder at widely separated points thereof, and 110 means for supporting an anvil between each of said hammers and said rim to transmit the blow of the hammer to the rim, said anvils being interconnected by an adjustable structure to adapt them to cylinders of different 115 diameters, and settable means being provided for adjusting the guiding means for cylinders of different diameters.

In testimony whereof I hereto affix my signature.

FRANCIS H. HUNT.
